UNITED STATES PATENT OFFICE.

CHARLES BONI, OF REGINA, SASKATCHEWAN, CANADA, ASSIGNOR OF ONE-THIRD TO
F. G. SADLEIR, OF REGINA, CANADA.

STOOKER.

1,356,503.

Specification of Letters Patent.

Patented Oct. 19, 1920.

Application filed July 2, 1918. Serial No. 243,003.

To all whom it may concern:

Be it known that I, CHARLES BONI, a subject of the King of Great Britain, and resident of the city of Regina, Province of 5 Saskatchewan, Dominion of Canada, have invented new and useful Improvements in Stookers, of which the following is a specification.

This invention relates to improvements in 10 stookers and the objects of the invention are, to facilitate mechanically collecting the desired number of sheaves and dumping the same in the form of a stook, to permit of the stooker being readily attached to binders at 15 present in use, and to provide means whereby the heads of the sheaves will be bunched during the operation of dumping, so that the sheaves will be deposited in the manner best calculated to form a proper stook. 20 Further objects are to automatically control the sheaves receiving means, so that after it has been dumped it will be automatically returned to its normal position preparatory to receiving the requisite number 25 of sheaves to form another stook, to simplify the arrangement of the several parts, and render them readily accessible for inspection and repair.

With the above and other objects in view 30 the invention consists essentially of the improved construction particularly described and set forth in the following specification and accompanying drawings forming part of the same.

35 In the drawings:

Figure 1 is a fragmentary end elevation of a binder showing the improved stooker attached thereto.

Fig. 2 is a plan view of the improved 40 stooker.

Fig. 3 is a side elevation of the improved stooker.

Fig. 4 is a fragmentary perspective view 45 of the guide and coacting rod slidably mounted thereon and designed to coact with the basket.

Like characters of reference refer to like parts in the several figures.

Referring to the drawings A represents a 50 part of a binder and B the improved stooker attached thereto stubble-ward of the binder deck 10.

The stooker B consists of a frame 11 which may be attached to the frame 12 of

the binder in any convenient manner and 55 the rear of the frame 11 is supported by the wheels 13 which engage with the ground.

Intermediate of the length of the frame 11 standards 14 are provided, carrying a transverse member 2 to which the smaller end of 60 the semi-conically shaped basket 15 is hinged as shown at 1, so that the said basket is capable of being rotated in a vertical plane.

This basket is provided on the lower wall with a guide 16 on which one end of the 65 curvilinear rod 17 is slidably mounted, the opposite end of the rod being secured by bolts to a crank member 19 journaled in the standard 20 mounted on the frame 11, and this crank member 19 is connected through 70 a flexible member 21 to a crank pin 22 of the sprocket 23 on the knotter shaft 24.

The flexible member 21 passes around 75 guide pulleys 25, secured to the frame 11, and, as the knotter shaft 24 rotates through one revolution, the basket 15 will be rotated into the position indicated by the dotted lines in Fig. 3.

The basket 15 is designed to be returned to its normal position by a tension spring 26 80 one end of which is connected to the rod 17, while the other end is anchored to the frame 11, and when in a normal position the rear end of the basket is supported by a suitable standard of brackets 3 of any convenient 85 construction.

On the opposite end of the frame 11 a second conically shaped basket 27 is provided, which carries a pair of ribs 28 attached to the lower walls thereof, and these ribs are 90 pivotally mounted intermediate of their length to the transversely extending rod 29.

The inner end of the ribs 28 are connected to the bail 30 and the free ends of the bail are connected by the rods 31 to the ends of 95 the crank member 32 pivotally mounted to the frame 11.

The bail 30 is further connected to one end of the dumping rod 33, the opposite end of which is attached to a foot trip 34, so that 100 on actuation of this trip the rod 33 will be moved longitudinally to rotate the basket 27 about the rod 29, and the basket will then assume a vertical position, as indicated by the dotted lines in Fig. 3.

This basket is returned to its normal position after dumping by the tension spring 35 which is connected at one end to the smaller

end of the basket 27, and at the other end to a curvilinear bracket 36 secured to the frame 11.

During the operation of dumping the basket 27, it is necessary that the forks 37 should be closed over the basket to hold the sheaves therein, and bunch the heads during the operation of dumping, and to this end I provide a curvilinear reinforcing band 38 which embraces the basket 27 and terminates in bifurcated ends 39, in which the shanks of the forks 37 are pivotally mounted.

The shank of the forks 37 are offset as shown at 40, and connected by springs 41 to the outer wall of the basket 27.

The forks 37 are closed by flexible members 42 connected at one end to the eyelets 43, and after passing around the guide pulleys 44, the other ends are connected to the arms 45 carried by the crank member 32, so that on rotation of the basket 27 in dumping, the crank member 32, is rotated through the rod 31 and rotates the arms 45 in a vertical plane, and thus exerts a pull on the flexible members 42 which rotate the forks 37 into the closed position indicated by the dotted lines in Fig. 1.

When the basket 27 is being returned to its normal position by the spring 35, the bail 30 will move the rod 31 and consequently rotate the crank member 32 into a normal position, so that the flexible members 42 will slacken off and allow the forks 37 to open under the action of the tension springs 41.

35 The assembly of the stooker will be readily understood from the foregoing description. When the stooker is in use the sheaves are discharged from the binder deck 10 into the smaller semi-conically shaped basket 15, and 40 during each rotation of the knotter shaft 24 the crank pin 22 will exert a pull on the flexible member 21, thereby rotating the crank member 19 and thus rotating the basket 15 in a vertical plane to transfer the 45 sheaves therein to the basket 27.

By reference to the drawings it will be seen the baskets 15 and 27 are in alinement with the smaller ends normally adjacent to each other and as the sheaves leave the binder deck 10, they are delivered with the heads toward the smaller end of the basket 15, so that on rotation of the said basket the sheaves will be delivered to the basket 27 with the heads at the smaller end and the 55 butts toward the larger end thereof, in which position the butts of the first sheaf or two delivered to the basket 27 will engage with the stop member 50 and thus prevent longitudinal displacement of the sheaves.

60 On the knotter shaft 24 continuing rotating the flexible member 21 will slacken, and the spring 26 returns the basket 15 to a normal position preparatory to receiving more sheaves which are in turn delivered to the 65 basket 27 in the manner above described.

When the basket 27 is filled with a desired number of sheaves the driver of the binder operates the foot trip 34 and so moves the rod 33 longitudinally, thereby rotating the basket 27 by means of the bail 30, around the transverse rod 29, and during this operation the rod 31 is moved and rotates the crank member 32 which in turn rotates the arms 45 and transmits a pull to the flexible members 42 so that the forks 37 are rotated about their pivoted points and close over the sheaves in the basket 27, and hold the same in the desired position during the operation of dumping.

When the basket 27 has reached a vertical 80 position the sheaves are dumped by gravity.

On the operator of the binder releasing the foot trip 34 the tension spring 35 returns the basket 27 to its normal position. During this operation the bail 30 will move 85 the rod 31 and so rotate the crank member 32 into its normal position, in which sufficient slack is allowed on the flexible members 42 to permit of the springs 41 rotating the forks 37 about their pivoted point, and leave the basket 27 open to receive sheaves from the basket 15.

This operation of dumping the basket 27 is repeated each time that a sufficient number of sheaves have been collected to form 95 a proper stook.

The construction of the stooker is extremely simple and the several parts are so arranged that they are readily accessible for inspection and not liable to go out of 100 repair.

As many changes could be made in the above description and many apparently widely different embodiments of my invention within the scope of the claims constructed without departing from the spirit or scope thereof, it is intended that all matter contained in the accompanying specification and drawing shall be interpreted as 105 illustrative and not in a limiting sense. 110

What I claim as my invention is:

1. In combination a basket for receiving sheaves, means for pivotally supporting said basket at its rear end, a rod slidably connected with the basket, a pivotal mounting 115 for the rod, a crank arm connected with the rod, a knotter shaft, a crank on the knotter shaft, a flexible connection from the first mentioned crank to the crank of the knotter shaft for tipping the basket at each revolution of the knotter shaft, and a spring for returning the basket to normal position. 120

2. In combination in apparatus of the class described, a dumping basket, to set sheaves upon the ground, a pivotal mounting for said basket, a crank arm, a foot crank, a connection between the crank arm and foot crank for tipping the basket, a spring for returning the basket to normal position, a pair of forks movable trans- 125 130

versely of the basket to hold the sheaves therein, a pivotal mounting for the said forks carried by the basket at the sides thereof, said forks having offset arms below 5 their pivots, springs connecting the said offset arms with the basket to hold the forks retracted, a crank arm mounted on the frame in front of the basket, flexible connections connected to and extending rearwardly from the crank arm, guides for directing the flexible connections laterally and upwardly, the upper ends of said flexible

connections being joined to the forks above the pivots thereof, and a connection from the basket to the said crank arm whereby 15 when the basket is tipped to deposit the sheaves the flexible connections will be operated by the crank arm to close the forks over the basket, substantially as described.

In witness whereof I have hereunto set 20 my hand in the presence of a witness.

CHARLES BONI.

Witness:

S. G. HADLIN.
